UNITED STATES PATENT OFFICE.

CLARENCE T. WALKER, OF ATLANTA, GEORGIA, ASSIGNOR OF ONE-HALF
TO GEORGE S. PRINDLE, OF WASHINGTON, D. C.

MACHINE FOR STRIPPING PEANUTS.

SPECIFICATION forming part of Letters Patent No. 319,762, dated June 9, 1885.

Application filed November 21, 1884. (No model.)

To all whom it may concern:

Be it known that I, CLARENCE T. WALKER, of Atlanta, in the county of Fulton, and in the State of Georgia, have invented certain new and useful Improvements in Machines for Stripping Peanuts; and I do hereby declare that the following is a full, clear, and exact description thereof, reference being had to the accompanying drawings, making a part of this specification, in which—

Figure 1 is a perspective view of my improved machine from the front. Fig. 2 is a plan view of the same. Fig. 3 is an elevation of the side at which the power is applied; 15 and Fig. 4 is a vertical section upon a line passing centrally through the longitudinal axis of said machine.

Like letters refer to like parts in all of the figures.

The object of my invention is to provide 20 means whereby peanuts can be easily, quickly, and thoroughly separated from the vines, the sound and perfect nuts separated from those which are imperfect and unsound, and the rubbish, refuse, and dirt separated and removed from the nuts; and to this end my invention consists in the machine and the construction, arrangement, and combination of its parts, as hereinafter set forth, and more 25 specifically pointed out in the claims.

In the annexed drawings, A and A represent 30 the top rails, B and B the bottom rails, C and C the posts, and D and D the cross-bars of the frame, of my machine, which parts are combined and have the general rectangular form shown.

Jounaled transversely across the upper 35 side of the frame described are four rollers, the first of which, E, is located near the rear end of said frame, the second, F, is placed near the opposite end of the same, while the remaining rollers, G and H, are placed, respectively, near said rollers E and F. The upper sides of said rollers E and F have the same plane, while said rollers G and H have their upper surfaces upon a plane slightly below the former.

Passing around the rollers E and F and over the rollers G and H are two endless belts, 40 I and I, which are placed near the ends of the

same and are connected together by means of bars or rods i and i, that are arranged transversely and at equal distances, and, when said endless belt or apron is caused to move lengthwise by the rotation of said roller E, are 55 caused to move in opposite directions with their contiguous surfaces nearly in contact.

At a point midway between the rollers E and F a roller, K, is journaled within vertically-adjustable bearings k, with its lower surface in contact with the upper face of the endless belt I, the object of which parts will be hereinafter explained.

Between the rollers G and H, beneath the belt I, is a hopper, L, which at its lower end 60 is connected with a box, M, that extends horizontally lengthwise of the frame, and at one end communicates with the casing n of a fan or blower, N, while at its opposite end said box is open.

Immediately below the lower end of the hopper L an opening, m, corresponding in size and shape to the like features of the former, is provided within the lower side of the box M, and beneath such opening is a screen, O, 65 composed of a series of longitudinal bars connected together so as to leave spaces between their contiguous sides, which screen is pivoted at one end to the lower side of said box, or to other suitable support, and from thence extends downward and outward with its lower end projecting outside of the frame.

The outer portion of the screen O is suspended by means of a bail, P, which permits the outer end of said screen to be moved lengthwise of the machine. A vibratory motion is imparted to said screen by means of a rod, Q, that is pivoted at one end to or upon the side of the former, and at its opposite end upon a crank, r, which crank is attached to and rotates with a shaft, R, that is journaled near the front end of the frame.

Motion is imparted to the operative parts of the machine by the following means, viz: a large pulley, S, provided with a crank, s, is 90 secured upon one end of the journal-shaft of the roller E, and around said pulley passes a belt, T, which also passes around a small pulley, U, that is secured upon the end of the shaft R opposite to the crank r.

Inside of the frame a large pulley, V, is secured upon said shaft, and from the same a belt, W, passes to and around a small pulley, X, which is attached to the shaft n' of the 5 blower N.

As thus arranged it will be seen that by turning the crank s the endless belt I will be caused to move around its rollers, the screen O will be vibrated, and the blower N will be 10 caused to revolve.

In use peanut-vines are placed upon the endless belt I in front of the roller K, when, by the operation of the rods i moving in opposite directions, the nuts will be separated from 15 the vines and will fall downward into the hopper L. The said roller K operates to hold said vines downward upon said belt, and to compel the nuts to project through between said rods so as to insure their separation from 20 said vines.

From the hopper L the nuts pass into the box M, where they are met by a current of air from the blower N, which current has such force as to cause the unsound lighter nuts to 25 pass forward out of the open end of said box, while the sound nuts, together with the heaviest of the dirt, fall through the opening m upon the screen O, said dirt then passing downward through the openings of said screen, 30 while said nuts pass outward upon the floor.

The light imperfect nuts possess a certain commercial value, and in order that they may be separated from dirt and other refuse matter I place at the open end of the box M a 35 trough, Y, which extends downward and inward to or near the floor, as shown in Figs. 1 and 4. The bottom of said trough terminates at or slightly below the bottom of said box, and upon said trough-bottom is provided a slide, y , 40 which fits between the sides of said trough, and is capable of such longitudinal adjustment as to cause its upper end to project to any required distance above the bottom of said box.

When the imperfect nuts reach the end of 45 the box M, they are caught by the projecting end of the slide y and caused to pass downward and inward beneath the frame, while such refuse matter as has been carried by the current of air beyond the opening m is caused to 50 pass outward over said slide, the result being the complete separation of said nuts from said refuse.

Having thus fully set forth the nature and merits of my invention, what I claim as new 55 is—

1. In a peanut-stripper, in combination

with a series of transverse bars, a series of transverse bars substantially at right angles to the other bar and flexibly connected together, and means, substantially as described, for 60 causing one of the series of bars to move longitudinally with reference to the other series of bars and close to the same, substantially as and for the purpose described.

2. In a peanut-stripper, as a means for separating the nuts from the vines, flexibly-connected transverse bars moving substantially at right angles to the bars, flexibly-connected transverse bars moving below and close to the other bars and in a direction opposite to that 70 of the movement of such other bars, and suitable driving means or mechanism, substantially as and for the purpose described.

3. As a means for separating the nuts from the vines, the endless belts I and I, provided 75 with the transverse connecting-rods i , and adapted to move longitudinally, with their contiguous portions moving in opposite directions, substantially as and for the purpose described.

4. In combination with the rollers E F, the rollers G H between them, the belts passing over and around rollers E F and over rollers G H, and the transverse bars connected with and carried by the belts, substantially as and 80 for the purpose described.

5. In combination with the two end rollers and the two intermediate rollers placed between them, the endless apron formed of the two belts carrying the transverse connecting-bars passing around the end rollers and up over the intermediate rollers, and the presser-roller above the upper portion of the belt passing between the end rollers, substantially 85 as and for the purpose described.

6. The hereinbefore-described machine for stripping, separating, and grading peanuts, comprising the operating-rollers E, F, G and H, endless belts I and I, having the transverse rods i , presser-roller K, hopper L, air-box M, 100 provided with opening m , blower N, screen O, and trough Y, having the slide y , all combined with each other and with operating mechanism, substantially as and for the purpose specified.

In testimony that I claim the foregoing I have hereunto set my hand this 25th day of June, 1881.

CLARENCE T. WALKER.
